SHOE TREE AND RACK

Hugh R. MacMichael, Piedmont, Calif.

Application February 27, 1937, Serial No. 128,241

14 Claims. (Cl. 12—128.5)

This invention relates to shoe trees and a supporting rack useable in combination therewith.

Some of the objects of this invention may be noted as the following: to provide a shoe tree and rack combination whereon a shoe may be treed with substantially as little effort as would be required to place it upon a shelf; and to provide said combination adapted for firmly attaching to a wall or other means of support, and thereafter adapted for use with substantially no manual handling or direct manipulation of any part of said combination for the treeing on or removal therefrom of a shoe.

Other objects are: to provide a tree which will subject said treed shoe only to light stresses effective to straighten it and smooth out the vamp by adjustable resilient pressure applied at longitudinally spaced points generally perpendicularly and vertically against respectively the toe insole, vamp, and shank of said shoe; to provide side members on said tree adapted to exert adjustable resilient pressure laterally outwards against the sides of the vamp part of the shoe; to effect said treeing stresses substantially free of harmful stretching effect in the treed shoe which latter is frequently observed with the use of shoe trees most commonly used heretofore; to provide a tree with highly resilient flexible and adjustable characteristics throughout adapting it for effective but harmless use for a considerable range in size, form and weight of shoes; and having the means of said adjustments simple, non-detachable and effective in respect both to the conformation and resilient characteristics of said tree, with the longitudinal adjustment operable even after a shoe is placed thereon and independently of the lateral adjustment.

Another object is to provide an effective, shoe-straightening tree useable in detached form which, by one hand, may easily be pushed directly into a shoe held in the other hand, said operation being devoid of the hitherto common necessity of thereafter having to flex and insert a powerful spring-supported or toggle-jointed member.

Other objects are to provide the aforesaid advantageous characteristics in said tree and rack in a design having very few parts, each and all suitable for quantity production, light in weight and low in cost. Other advantages will become apparent.

Illustrating my invention are the drawings herewith in which

Fig. 1 is a front elevation of a horizontal wall-rack combination having a pair of shoe trees;

Fig. 2 is a plan of Fig. 1;

Fig. 3 is a perspective view of a shoe tree mounted on a short length of wall-rack;

Fig. 4 is an enlarged side elevation of the shank-spring ratchet slide partly in section;

Fig. 5 is a reduced front elevation of the device arranged for a vertically-extending rack;

Fig. 6 is a plan of Fig. 5;

Fig. 7 is a side elevation of the shoe tree in another mode provided with adjustable side members;

Fig. 8 is a partial plan looking upward to Fig. 7; and

Fig. 9 is a cross-section taken on the line 9—9 of Fig. 7. 15

Referring to the drawings, a shoe-tree body 10 is provided with a forward part 11 having the shoe-contact surfaces 12 and 13 adapted respectively to contact downward on the toe-end insole (contact 12) and upward against the vamp (contact 13) of a treed shoe. Said body 10 has the rearwardly-extending arm part 14 notched on its lower side to form the ratchet teeth 15.

The rear end 16 of said arm 14 is adapted for fixed mounting in the socket 17 of the supporting rack-arm 18 extending crosswise from the mounted shoe-tree to a fixed attachment on the rack 20 which latter may carry a plurality of said rack arms suitably spaced on its length. Said rack 20 may be screwed to a supporting wall or wardrobe door 22 or provided with other means of support.

A longitudinally - extending highly - flexible spring shank member 25 is attached at its forward end 25a to the lower side of said body toe-end 11, and at its rear end 25b is attached to an encircling ratchet pawl slide 27 which latter loosely encircles said notched arm 14 for adjustably positioned support thereon. Said slide 27 is provided on its lower rear part with the pawl projection 28, adapted to engage upward with one of said ratchet teeth 15, and the forwardly spaced upper fulcrum part 29 of said encircling slide 27, adapted to contact downward on the top of said arm 14. Under resilient pressure exerted by said attached shank-spring 25, said slide pivots downward on its said forward fulcrum part 29 thereby rotating its rearward pawl part 28 up into engagement with said arm teeth 15 adapted to prevent rearward movement of said engaged ratchet slide 27. A user may readily disengage said pawl to allow it resiliently to move rearward, or by a direct push he may slide it forward against the pressure of said shank spring.

In fully extended position to the rear, said 55

shank spring 25 will resiliently flatten out and lie generally parallel and but slightly stressed adjacent the underside of said body 10. As said slide 27 is ratcheted adjustably forward, it will 5 force said spring shank 25 into an increasingly stressed generally semi-elliptical form which in its mid-length 30 is adapted to contact downward against the shank part of a treed shoe. In its extreme forward position said spring 25 will approximate the form illustrated by dotted lines 31 10 (see Fig. 1).

The arrangement as shown in Fig. 1 is for treeing a pair of shoes with latter positioned respectively heel-to-heel, and it is adapted for 15 use only in a horizontal position. If it were turned to the vertical, one of the shoes would fall off. The shoe also positions generally horizontally and is entirely supported, against gravity and the downward pressures of the shank contact 30 and the toe contact 12, by means of the upwardly pressing vamp contact 13. Most of the shoe cantilevers back from said supporting contact 13, and the weight thus overhung tends to straighten the shoe and thereby materially reduces the shoe-straightening force otherwise required from said shank spring 25 contacting the shoe shank at 30. This effect is highly advantageous in permitting the use of a lighter spring, and particularly so in requiring less resiliently 25 exerted pressure thereby minimizing the tendency (which would exist with a stronger spring) to apply so much resilient pressure to a shoe as injuriously to "over-straighten" and distort it.

The shank-spring 25 form and resultant shoe-straightening stress may be adjusted even after a shoe is treed on this device, as the adjusting ratchet slide 27 is always readily accessible (see Fig. 1). Once adjusted however, nothing remains to be done but to slip the shoe on and off the tree 40 until a substantially different size, form or type of shoe to be treed makes a different adjustment desirable.

Said tree may also be used unmounted in which case a knob or loop may be attached on the arm 45 end 16 for convenience in grasping manually.

In another arrangement (see Figs. 5 and 6) the device may be constructed with a vertically extending rack 33 provided with a plurality of vertically-spaced said rack-arms 18 adapted to 50 carry said shoe-tree bodies 10 extending alternately to the right and to the left.

While I have shown said spring 25 as being firmly attached at the toe-end and adjustably attached at the always-accessible rear end, in 55 respect simply to adjustment the arrangement is obviously reversible, and the rear end could be firmly attached and the forward end made adjustably positioning.

In another mode laterally resilient and adjustable (see Figs. 7, 8, and 9) the shoe tree body 40 is provided with the forward part 41 having the shoe-contact surfaces 42 and 43 adapted respectively to contact downward on the toe-end insole (contact 42) and upward against 60 the vamp (contact 43) of a treed shoe. Said body 40 has the rearwardly extending arm part 44 notched on its lower side to form the ratchet teeth 45 engageable with the arm-encircling ratchet slide 46 attached to the rear-end of the shank spring 47 adapted at its flexed middle part 47a to contact downward against the shank part 65 of a shoe, and screwed at its forward end 47b on the projecting lug 50 on the underside of said body forward part 41. The rear-end of said 70 arm 44 may be mounted on a fixed rack support 75

(see Fig. 3) or it may be provided with a knob 52 adapted for conveniently handling the tree when not mounted.

Differing from said shoe-tree body 10 of Fig. 1, the body 40 (see Figs. 7, 8, and 9) is provided with the hinged sides 60 each attached at the upper edge by the hinge members 61 and 62, each of said hinged sides being independently adjustably resiliently moveable inwardly as indicated by position lines 60a and outwardly as indicated by lines 60b. Said sides 60 are provided with the inwardly-extending rearwardly-positioned perforated lugs 65 engaging the rear-ends of the "wish-bone" wire spring 66 whose forward ends loosely encircle said body lug 50 and is retained loosely in place thereabout by the underlying said screwed-on shank spring end 47b. Extending across between the sides of said spring 66 is the adjusting member 70 whose encircling end parts 71 and 72 are longitudinally adjustably positioned on said spring 66 by means of the slideable resilient split-ring clinch collars 73. Said adjusting member part 71 is threaded to engage the sleeve nut 74 also slidably engaged by the ball-end 75 of said part 72.

In use, said lateral adjustment is workable (a) by a variable longitudinal positioning of one or both ends of said adjustment member 70 along the sides of said "wish-bone" spring 66; (b) by means of said sleeve nut 74 adapted to limit the maximum width of the tree while permitting a resiliently-resisted narrowing thereof; and (c) by permitting said hinged sides 60 to position themselves, relative to the longitudinal axis of the tree body 40, adaptably for either right or left shoes. The advantages of the foregoing are found by test to be substantial, and especially in said tree having also the separately-adjustable longitudinal shoe-straightening means.

The longitudinal straightening with my tree is done by means of lightly exerted pressures perpendicularly applied at three spaced points along the length of the shoe, and an effective straightening de-wrinkling tension is thus exerted on the shoe vamp while completely avoiding the useless harmful longitudinal stretching of the whole shoe as frequently produced by other types of trees.

The adjustable resiliently pressing side members need exert only a very light lateral pressure (substantially lighter than said longitudinally straightening pressures) thereby lightly holding the sides of the shoe vamp distended, smooth and free of wrinkles.

Said lightly exerted longitudinal and lateral pressures effective with my tree are in striking contrast to those heavy pressures exerted by the conventional powerfully acting shank-spring or toggle-jointed shoe-tree members exerting an indeterminate force unnecessarily stretching a shoe length-wise; which force in some trees is used even more powerfully by applying it to laterally acting wedge-like members, severely straining the stitching in a shoe while accomplishing no good purpose not harmlessly secured by my lightly laterally-pressing tree.

I have found that various modifications, substitutions and transpositions may be made in the preferred construction of my device herein set forth, and others may occur to those skilled in mechanical arts. For instance, for obtaining adjustment of the resilient characteristics and form of spring, various mechanical details including slideable levers or wedges, rotatable eccentrics and others are adaptable, some of such alternatives

being disclosed in my pending application Ser. No. 69,679 of March 19, 1936.

Having described a novel shoe tree, optionally in combination with supporting means, adapted 5 for use with an ease and convenience which I have been unable to discover elsewhere, I wish to claim broadly the principles of construction pertaining thereto.

What I claim is:

- 10 1. A shoe straightening tree comprising a longitudinally-extending body; contact surfaces on said body adapted to contact downward against the toe insole and upward against the vamp of a treed shoe; a flexible spring member attached 15 at its ends to said body, and in its middle part adapted to exert resilient pressure downward on the shank of a treed shoe; and means including a ratchet device whereby one of said attached ends may be longitudinally adjustably positioned 20 on said body.
2. A shoe straightening tree comprising a longitudinally-extending body; contact surfaces on said body adapted to contact downward against the toe insole and upward against the vamp 25 of a treed shoe; a flexible spring member attached at its ends to said body, and in its middle part adapted to exert resilient pressure downward on the shank of a treed shoe; and means including a ratchet device whereby one of said 30 attached ends may be longitudinally adjustably positioned on said body; said spring member being adapted also to exert resilient pressure for holding said ratchet device in engagement.
3. A shoe straightening tree comprising a longitudinally-extending body; contact surfaces on 35 said body adapted to contact downward against the toe insole and upward against the vamp of a treed shoe; a generally semi-elliptic longitudinally-extending spring member attached at its 40 ends to said body and in its middle part adapted to exert resilient pressure downward on the shank of a treed shoe; and means including a ratchet device whereby one of said attached ends may be longitudinally adjustably positioned on 45 said body.
4. A shoe straightening tree comprising a longitudinally-extending body; contact surfaces on 50 said body adapted to contact downward against the toe insole and upward against the vamp of a treed shoe; a generally semi-elliptic longitudinally-extending spring member attached at its ends to said body and in its middle part adapted to exert resilient pressure downward on the shank of a treed shoe; and means including a 55 ratchet device whereby one of said attached ends may be longitudinally adjustably positioned on said body; said spring member being adapted also to exert resilient pressure for holding said ratchet device in engagement.
5. A shoe straightening tree comprising a longitudinally-extending body; contact surfaces on 60 said body adapted to contact downward against the toe insole and upward against the vamp of a treed shoe; an extending arm part of said body adapted to the generally rigid support thereof from external supporting means; a generally semi-elliptic longitudinally-extending spring member having one end attached near the forward end of said body, adapted in its mid-length 65 to exert pressure contact downward on the shank of a treed shoe; and ratchet means attached to the rear end of said spring, slidably mounted on said arm.
6. In a shoe straightening tree and wall rack 70 combination comprising a shoe tree adapted to be inserted in a shoe and to make therein longitudinally-spaced pressure contacts respectively downward on the toe end and the shank part, and upward on the vamp of a treed shoe; a rearwardly extending arm part of said tree; a wall rack having an outwardly extending rack-arm 75 adapted to the fixed support of said tree-arm with said tree occupying a generally horizontal position wherein a treed shoe may be supported against gravitation by said vamp contact, with the overhanging rear part of said shoe gravitationally exerting a shoe-straightening force in cooperation with the like force exerted by said downward pressure contact on said shoe shank.
7. A shoe tree having a central longitudinally-extending body part, adapted to be inserted in a shoe; side contact members hinged to said body enabled to swing about longitudinally extending axes to press adaptably against the vamp sides of said shoe; spring means adapted to exert resilient pressure outwards on said hinged members; and means adapted to limit the outward spreading movement of and between said hinged members.
8. A shoe tree having a central longitudinally-extending body part, adapted to be inserted in a shoe; side contact members hinged to said body enabled to swing about longitudinally extending axes to press adaptably against the vamp sides of said shoe; spring means adapted to exert resilient pressure outward on said hinged members; and means adapted adjustably to limit the outward spreading movement of and between said hinged members.
9. A shoe tree having a central longitudinally-extending body part, adapted to be inserted in a shoe; side contact members hinged to said body enabled to swing about longitudinally extending axes to press adaptably against the vamp sides of said shoe; spring means adapted to exert resilient pressure outward on said hinged members; and means of adjustment acting on said spring means adapted to control the resilient pressure characteristic thereof.
10. A shoe tree adapted to be inserted in a shoe for the smoothing straightening thereof comprising vertically acting contact parts adapted respectively to exert downward pressures on the toe-end insole and the shank part, and upward pressure on the vamp part of a treed shoe; side contact members of said tree hinged thereon to swing about longitudinally extending axes, enabled to exert lateral pressure adaptably on the vamp sides of said shoe; spring means affecting all said contacts adapted to sustain thereon resilient pressure; and means of adjustment acting on said spring means adapted to control the resilient pressure characteristics thereof.
11. A shoe tree adapted to be inserted in a shoe for the smoothing straightening thereof comprising vertically acting contact parts adapted respectively to exert downward pressures on the toe-end insole and the shank part, and upward pressure on the vamp part of a treed shoe; side contact members of said tree hinged thereon to swing about longitudinally extending axes, enabled to exert lateral pressure adaptably on the vamp sides of said shoe; spring means affecting all said contacts adapted to sustain thereon resilient pressure; and means of adjustment acting on said spring means adapted to control the resilient pressure characteristics thereof.
12. A shoe tree having a central longitudinally-extending body part, adapted to be inserted in a shoe; side contact parts of said tree enabled to regulate the relative positioning thereof.
13. In a shoe straightening tree and wall rack combination comprising a shoe tree adapted to

- swing out laterally to press adaptably against the vamp sides of said shoe; and means of adjustment whereby said lateral swinging of said side parts may be adjustably limited.
5. 13. A shoe tree having a central longitudinally-extending body part, adapted to be inserted in a shoe; side contact parts of said tree enabled to swing out laterally to press adaptably against the vamp sides of said shoe; spring means adapted to exert resilient pressure outward on said side parts; and means of adjustment whereby said lateral swinging of said side parts may be adjustably limited.
10. 14. A shoe tree having a central longitudinally-extending body part, adapted to be inserted in a shoe; side contact parts of said tree enabled to swing out laterally to press adaptably against the vamp sides of said shoe; spring means adapted to exert resilient pressure outward on said side parts; and means of adjustment acting on said spring means adapted to control the resilient pressure characteristics thereof.

10

HUGH R. MACMICHAEL.
